UNITED STATES PATENT OFFICE.

JOSEPH KOPPE, OF CANTON, OHIO.

ADJUSTABLE PAD FOR SHOE-TONGUES.

1,255,616.

Specification of Letters Patent.

Patented Feb. 5, 1918.

Application filed July 9, 1917. Serial No. 179,330.

To all whom it may concern:

Be it known that I, JOSEPH KOPPE, a citizen of the United States, residing at Canton, in the county of Stark and State of Ohio, have invented a new and useful Adjustable Pad for Shoe-Tongues, of which the following is a specification.

The present invention relates to improvements in pads for shoe tongues and has more especial reference to an adjustable and detachable pad which may be easily and quickly attached to the tongue of a shoe and easily adjusted to accommodate shoes of various sizes and styles.

15 The object of this invention is to provide a pad upon a shoe tongue which will prevent injury to the instep or ankle of the wearer and which may be adjusted to fit the tongues of shoes of different sizes and styles.

20 A further object is to provide an adjustable pad for shoe tongues which may be easily and readily applied to the tongue of any shoe and quickly adjusted to bring the thicker portion of the pad over any desired 25 part of the instep or ankle to cause the shoe to be evenly laced.

With these objects in view the invention consists in the novel construction and arrangement of parts, hereinafter described, 30 illustrated in the accompanying drawings, and particularly pointed out in the appended claims, it being understood that various changes in the form, proportions, size and minor details of construction may be made 35 within the scope of the appended claims, without departing from the spirit or sacrificing any of the advantages of the invention.

In the accompanying drawings:

Figure 1 is a perspective view of my adjustable shoe tongue pad.

Fig. 2 is a detached elevation of a shoe tongue, showing my pad attached thereto.

Fig. 3 is a side elevation of the same.

Similar numerals of reference indicate 45 corresponding parts throughout the several figures of the drawings.

Referring more especially to the construction illustrated in the accompanying drawings, the numeral 1 indicates the attaching strip which is preferably formed of stiff flexible material such as crinoline, buckram or the like and provided with a tape binding 50 2. The attaching strip is provided adjacent each extremity with suitable attaching means such as the clips 3, which are arranged 55 to be passed through the tongue 4 as shown

in Fig. 2 and bent back upon the outer face of the tongue, thus holding the attaching strip permanently in place upon the inner face of the tongue.

The upper and lower pad members 5 and 6 respectively are formed of felt or other suitable material and preferably shaped as best shown in Fig. 1 of the drawings and are slidably connected to the attaching strip 1 by means of bands 7 and 8 respectively which are formed of tape or other suitable material, a similar band 9 being connected to the upper member 5 and located around the lower member 6. In this manner the upper 60 and lower pad members 5 and 6 may be adjusted with reference to each other and to the attaching strip 1 in order to be easily and quickly adjusted to tongues of different lengths and to adjust the overlapping portions of the pad members so as to bring this thickened portion of the pad at any desired 65 place over the instep or ankle of the wearer in order to properly fill the shoe so that the same may be laced evenly to present a neat 70 appearance upon the foot.

It will, of course, be understood that these pads will be made in different sizes for men's and women's shoes as well as children's shoes and that shorter sizes will be made to accommodate Oxford or other low shoes. The attaching clips 3 may be enameled in different colors to accommodate all shades of 85 shoes in order that these attaching clips will not be noticeable upon the tongue of the shoe. 90

Although the accompanying drawings show clips 3 which are arranged to attach the attaching strip to the tongue of the shoe it will be understood that these strips may be attached by stitching to the tongue if desired, thus making a neater finish, the clips being merely provided for purpose of convenience where it is not desired to stitch the strip to the tongue.

Although the drawings and above specification disclose the best mode in which I have contemplated embodying my invention I desire to be not limited to the details of such disclosure, for in the further practical application of my invention, many changes 100 in form and construction may be made, as circumstances require or experience suggests, without departing from the spirit of the invention, within the scope of the appended claims.

110
I claim:

1. An article of the character described

comprising an attaching strip adapted to be connected to the inner face of a shoe tongue, a pair of pad members formed of soft flexible material, the adjacent extremities of said pad members arranged to overlap, straps formed upon said pad members and extending around said attaching strip and a strap connected to one of said pad members and extending around the other of said pad members.

10 2. An article of the character described, comprising a relatively adjustable pair of pad members formed of soft, flexible material and means for connecting said pad members to a shoe tongue.

15 3. An article of the character described, comprising an attaching strip, a pair of relatively adjustable pad members, means for connecting said attaching strip to a shoe tongue and means for connecting the said pair of relatively adjustable pad members to the said attaching strip.

20 4. An article of the character described, comprising an attaching strip adapted to be

connected to the tongue of a shoe, a pair of 25 relatively adjustable pad members formed of soft, flexible material, means for attaching the relatively adjustable pad members to the attaching strip and means for holding the relatively adjustable pad members in 30 adjusted position on the attaching strip.

5. An article of the character described, comprising an attaching strip, a pair of relatively adjustable pad members formed of soft, flexible material, means for holding the 35 pad members in adjusted position on the attaching strip and means for attaching the pad members to a shoe tongue.

6. An article of the character described, comprising an attaching strip, a pair of 40 relatively adjustable pad members formed of soft, flexible material, means for holding the pad members in adjusted position on the said attaching strip and means for securing the said attaching strip to a shoe tongue. 45

In testimony that I claim the above, I have hereunto subscribed my name.

JOSEPH KOPPE.
